UNITED STATES PATENT OFFICE.

WILLIAM D. THOMPSON, OF DETROIT, MICHIGAN, ASSIGNOR, BY MESNE ASSIGNMENTS, TO HUTCHINS CAR ROOFING COMPANY, OF DETROIT, MICHIGAN, A CORPORATION OF DELAWARE.

RUNNING-BOARD SADDLE.

Application filed June 22, 1925. Serial No. 38,896.

The invention relates to running board saddles and more particularly to an improved construction of a combination saddle and center joint cap.

5 The invention has among its objects to simplify, render more efficient, and improve generally devices of this character, and these as well as other objects, advantages, and novel details of construction will be made more apparent as this description proceeds, especially when considered in connection with the accompanying drawings, wherein

10 Figure 1 is a fragmentary plan view of a car roof showing my improved invention,

15 Figure 2 is a sectional view taken substantially on the plane indicated by line 2-2 in Figure 1,

20 Figure 3 is a sectional view taken substantially on the plane indicated by line 3-3 in Figure 1, and Figure 4 is a separated perspective view of certain of the parts of the device.

25 Referring now particularly to the drawings wherein like reference characters indicate like parts, and wherein further only so much of the car roof and frame construction is illustrated as is sufficient for a complete understanding of the present invention, it will be noted that there is shown a ridge 30 pole 10 and a carline 11 of the roof frame, the latter being of a substantially inverted U-shape and shown as secured to the ridge pole by means of bolts 12. The roof sheets 13 in the herein illustrated construction are 35 formed of metal and are adapted to be loosely supported to form a flexible roof structure and are therefore provided with upstanding flanges 14 on their inner and side edges adapted for cooperation with ridge caps 15 40 and carline caps 16 in the customary manner for weatherproofing the joints between transverse and longitudinally adjacent roof sheets.

45 The present invention relates specifically to means for weatherproofing the junction of the ridge caps and carline caps and for affording means for supporting the running board. To this end I provide a junction cap member 17 shaped to form crossed channel portions adapted to embrace the carline caps and ridge caps respectively. To this end the junction cap is formed with channel portions 50 18 substantially inverted U-shaped in cross section which extend in the direction 55 of the carline caps 16 and are adapted to

straddle the inner ends of these carline caps in the manner shown particularly in Figure 2. The crossed or transversely extending channel portions 19 which are also substantially of inverted U-shape straddle the adjacent ends of ridge caps 15 as more clearly shown in Figure 3. The channel portions 18 are inclined downwardly in an outward direction from a central portion 20 of cap member 17 into which these channel portions 60 18 merge. The inclination of channel portions 18 corresponds to the inclination of the roof and consequently of the carline caps from the ridge pole outwardly to the eaves. The channel portions 19 also merge into the 65 central portion 20 of cap member 17 and are slightly inclined as shown.

70 The portion 20 of cap member 17 is formed with a centrally arranged upstanding boss 21. This boss surrounds an aperture 22 through which bolt 23 is adapted to be passed. This bolt passes downwardly through a saddle bracket 24, the head 25 of the bolt engaging an apertured upwardly extending depression or protuberance 26 75 which forms a pocket of sufficient dimensions to surround boss 21. Bracket 24 is substantially U-shaped as shown in Figure 2 and is formed with horizontally arranged flanges 27 adapted to be bolted to a saddle 80 plate 28 arranged substantially horizontally. Saddle plate 28 is formed with a downwardly directed projection 29, formed preferably by cutting and deforming or bending the metal, which bears against a saddle bolt cap 90 30 arranged over the head 25 of saddle bolt 23 for weatherproofing the latter to prevent the passage of moisture downwardly through the bolt apertures. Saddle plate 28 rests also upon horizontally arranged flanges 95 31 formed on the ends of upwardly directed extensions 32 of the junction cap member 17, these projections 32 and flanges 31 being preferably continuations of the upper wall of channel portions 18. In forming the 100 junction cap member 17 it is preferably laterally elongated so that the flanged ends 31 may be sufficiently spaced to adequately support the ends of saddle plate 28. The running boards 33 rest upon saddle plate 28 105 and are secured in place by bolts 34, selected ones of which pass also through the horizontal flanges 27 and 31 for securing saddle plate 28 to these parts.

110 Saddle bolt 23 is adapted to extend down-

wardly through suitable apertures formed in the ridge pole 10 and the adjacent carline 11 and is threaded to receive a nut 35 by means of which the structure is secured in 5 position.

In assembling the parts a washer in the form of a canvas sheet 36 is positioned so as to extend entirely under cap member 17 and to thus interpose itself between this member 10 and the adjacent ends of ridge caps 15 and carline caps 16. This not only assists in weatherproofing the joints between these parts but eliminates the direct metal to metal engagement which would otherwise result.

15 The saddle plate 28 is formed with transversely spaced rows of apertures 37 through which the bolts 34 may be passed, this transverse spacing of the bolt holes 37 permitting a splicing of the running boards when nec- 20 essary.

With the saddle plate 28 secured to saddle bracket 24 and also to junction cap member 17, and with this latter member in position so as to engage, in a weatherproofing 25 manner, the adjacent ends of the carline and ridge caps, the saddle bolt 23 may then be drawn down tightly by a nut 35 whereupon saddle bracket 24 is drawn tightly against cap member 17 and the latter is caused to 30 tightly and embracingly engage the ends of the ridge and carline caps. Thus the junction of these caps is properly weather- 35 proofed and the structure thus employed for weatherproofing is also utilized as a part of the running board saddle whereby support for the running boards is provided.

The device is distinguished by its simplicity, durability and the facility with 40 which the same may be manufactured, assembled and installed, and further by its efficiency in operation.

While an embodiment of the invention has been illustrated and described herein in some detail, it will be immediately apparent 45 that various modifications and changes may be resorted to without departing from the spirit and scope of the invention and to this end reservation is made to make such changes as may come within the purview of 50 the accompanying claims.

What I claim as my invention is:

1. In a car roof, a sheet metal junction cap formed with spaced upwardly extending laterally flanged projections, and a running board plate secured to said projections, 55

said parts constituting a running board saddle.

2. In a car roof, a sheet metal junction cap formed with laterally spaced upwardly extending projections terminating in horizontal flanges, and a running board plate secured to said flanges, said parts constituting a running board saddle. 60

3. In a car roof, the combination with carline and ridge caps, of a junction cap, and a flexible washer arranged between said junction cap and carline and ridge caps. 65

4. In a car roof, a junction cap formed with upturned horizontally flanged ends, a similarly flanged saddle bracket on said cap intermediate said flanged ends, and a saddle plate mounted on said flanges and secured thereto. 70

5. In a car roof, a junction cap formed with upturned horizontally flanged ends, a similarly flanged saddle bracket on said cap intermediate said flanged ends, registering apertured bosses formed on said junction cap and saddle bracket, and a saddle bolt 75 engaging said apertures for securing said parts to the ridge pole. 80

6. In a car roof, a junction cap, spaced upwardly extending projections on said cap, a bracket on said cap intermediate said projections, and running boards supported on 85 said projections and bracket.

7. In a car roof, a junction cap formed with laterally spaced upwardly extending projections, a saddle bracket on said cap intermediate said projections, and a saddle 90 plate secured to said projections and bracket.

8. In a car roof, a junction cap formed with laterally spaced upwardly extending projections, a saddle bracket on said cap intermediate said projections, a saddle plate secured to said projections and bracket, and means passing through said saddle bracket and cap and engaging the ridge pole for securing said parts in place. 95

9. In a car roof, a junction cap formed with spaced supporting flanges, a saddle plate mounted thereon, a headed saddle bolt engaging an aperture formed in said junction cap, a saddle bolt cover for the head of said bolt, and a projection on said saddle plate engaging said cover. 100

In testimony whereof I affix my signature.

WILLIAM D. THOMPSON.
